UNITED STATES PATENT OFFICE.

CHARLES ZIEGLER, OF LIMOGES, FRANCE, ASSIGNOR TO THE J. POUYAT COMPANY, OF NEW YORK, N. Y., A CORPORATION OF NEW YORK.

DESIGN FOR A PLATE OR SIMILAR ARTICLE.

40,397.

Specification for Design.

Patented Dec. 14, 1909.

Application filed October 25, 1909. Serial No. 524,583. Term of patent 7 years.

To all whom it may concern:

Be it known that I, CHARLES ZIEGLER, a citizen of France, residing in Limoges, France, have invented a new, original, and ornamental Design for a Plate or Similar Article, of which the following is a specification, reference being had to the accompanying drawing, forming a part thereof.

The figure is a plan view of the plate or similar article, showing my design.

I claim:

The ornamental design for a plate or similar article, as shown.

CHARLES ZIEGLER.
